UNITED STATES PATENT OFFICE.

JAMES H. HALE, OF COLUMBUS, GEORGIA, ASSIGNOR OF THREE-EIGHTHS TO THOMAS J. FARLEY, THREE-EIGHTHS TO SAMUEL T. WHITAKER, AND ONE-FOURTH TO JAMES M. CRAWFORD, ALL OF COLUMBUS, GEORGIA.

SHUTTLE-BRUSH.

1,166,204.

Specification of Letters Patent. Patented Dec. 28, 1915.

Application filed August 18, 1914. Serial No. 857,418.

To all whom it may concern:

Be it known that I, JAMES H. HALE, a citizen of the United States, residing at Columbus, in the county of Muscogee and 5 State of Georgia, have invented a new and useful Improvement in Shuttle-Brushes, of which the following is a specification.

My invention relates to improvements in shuttle brushes, and its object is to prevent 10 the thread or filling on the quill from coming off in wads, getting tangled and causing bad cloth, as heretofore. I attain this and other objects by the mechanism shown in the accompanying drawing, in which—

15 Figure 1 is a plan view; Fig. 2 a side elevation; Fig. 3, a plan showing how the brush material is bent to form a loop end to the brushes, and Fig. 4 a cross section on line A—B.

20 Similar numerals refer to similar parts throughout the several views.

1 is a shuttle; 2 is a quill which carries the filling 8, and is secured inside of the said shuttle 1, in the usual manner.

25 3, 4 and 5, are brushes made by bending a number of strands of suitable brush material and bunching them together, after which they are secured inside of the said shuttle 1, so they will exert a slight pressure on the 30 top and bottom of the said quill 2, and filling 8, which prevents the said filling 8, from slipping off or unwinding in wads.

6 and 7 are brushes which are composed of cotton, felt or other soft material secured 35 in the said shuttle 1, in such a manner that the thread or filling 8, must pass between them as it is paid out, which helps to keep it straight.

The important feature of this invention is 40 the double strands of brush material, which keeps a slight tension on the said filling 8, and at the same time prevents it from getting tangled in the brush itself.

Brushes have been tried before, but with 45 the sharp or loose ends against the filling, but that was not a success, because the filling would get in between the loose ends of the said brushes and break, but I overcome this trouble by doubling the strands of brush 50 material which makes them so springy the filling cannot get between the strands.

Having thus described my invention what I claim as my own and desire to secure by Letters Patent is:

1. In a shuttle brush the combination of 55 one or more primary brushes composed of suitable brush material, with each strand doubled to form a loop end, and having the loose ends of the said brush material adapted to be secured to the inside of the shuttle in 60 such a manner as to cause a slight tension on the thread or filling as it is paid out of the said shuttle, with one or more secondary brushes composed of cotton, felt or other soft material, and secured in the said shuttle 65 in such a manner that the thread or filling must pass between them as it is paid out of the said shuttle, substantially as shown and described.

2. In a shuttle, the combination, with a 70 body having a bobbin chamber and a yarn feeding opening leading therefrom, of a brush formed of a strand of brush material, looped and having the looped portion disposed to contact with yarn being fed from 75 the bobbin chamber.

3. In a shuttle, the combination, with a body having a bobbin chamber and a yarn feeding opening leading therefrom, of a brush formed of strands of brush material, 80 looped and having the looped portions disposed to contact with yarn being fed from the bobbin chamber, and the ends fixed to the shuttle body.

4. In a shuttle, the combination, with a 85 shuttle body, having a bobbin chamber and a yarn feeding opening leading therefrom, of brushes connected to said body and disposed at substantially opposite sides of the chamber for engaging relatively opposite portions 90 of material on a bobbin in said chamber, each of said brushes being formed of strands looped and provided with the looped portions extending to position for contacting with the material on the bobbin. 95

In testimony that I claim the foregoing as my own, I have hereto affixed my signature in the presence of two witnesses.

JAMES H. HALE.
